UNITED STATES PATENT OFFICE

BORNETT L. BOBROFF, OF RACINE, WISCONSIN

DESIGN FOR A VEHICLE LIGHT

Application filed March 31, 1930. Serial No. 35,088. Term of patent 14 years.

To all whom it may concern:

Be it known that BORNETT L. BOBROFF, a citizen of the United States, residing at Racine, in the county of Racine and State of Wisconsin, has invented a new, original, and ornamental Design for Vehicle Lights, of which the following is a specification, reference being had to the accompanying drawings, forming part thereof.

Figure 1 is an edge view of the vehicle light showing my new invention.

Figure 2 is a face view.

Figure 3 is a top view.

I claim:

The ornamental design for a vehicle light, as shown.

BORNETT L. BOBROFF.
